UNITED STATES PATENT OFFICE.

JOHN HAYS HAMMOND, JR., OF GLOUCESTER, MASSACHUSETTS.

METHOD OF AND SYSTEM FOR SELECTIVE WAVE TRANSMISSION.

Application filed April 26, 1912, Serial No. 693,380. Renewed December 21, 1918. Serial No. 267,874.

To all whom it may concern:

Be it known that I, JOHN HAYS HAMMOND, Jr., a citizen of the United States, residing at Gloucester, in the State of Massachusetts, have invented certain new and useful Improvements in Methods of and Systems for Selective Wave Transmission, of which the following is a specification.

My invention relates to improvements in methods of and systems for transmitting energy by means of electro-radiant waves, and relates more particularly to systems wherein selectivity in transmission is secured by employing distinctive wave lengths and distinctive wave-group frequencies. In such systems I secure a still higher degree of selectivity by transmitting and receiving these waves and wave groups at a definite set rate by means of interrupters, located either at the transmitting or the receiving stations, as is hereinafter more fully set forth.

Fig. 1 shows, in diagrammatic form, a transmitting station capable of sending out electric waves of two different lengths or wave frequencies at two different group frequencies.

Fig. 2 shows, in diagrammatic form, a receiving station for receiving waves of two different lengths at two different group frequencies, and at a definite set rate by means of interrupters.

Fig. 3 shows, in diagrammatic form, a receiving station for receiving waves of two different lengths at two different group frequencies, and at a definite set rate by means of interrupters, but with a modified form of receiving apparatus.

Fig. 4 shows, in diagrammatic form, a transmitting station for sending out electric waves of two different lengths at two different group frequencies, and at definite set rates by means of interrupters.

Fig. 5 shows, in diagrammatic form, a receiving station adapted to receive waves of two different lengths at two different group frequencies and at definite set rates, as transmitted from a station such as shown in Fig. 4.

Fig. 6 shows, in diagrammatic form, a

modified form of transmitting station for sending out two or more groups of electric waves of different lengths, at different spark, or group frequencies, with the use of only one alternating current generator instead of two.

In Fig. 1, A is an antenna grounded at E, and inductively connected, by means of the coils L^3 and L^4 , with the oscillatory circuits $L^1 S^1 C^1$ and $L^2 S^2 C^2$, respectively. G^1 is an alternating current generator, which when the key K^1 is closed, furnishes current of a definite frequency to the step-up transformer, T^1 , which charges condenser C^1 . $L^1 S^1 C^1$ is an oscillatory circuit having a predetermined frequency of oscillation, and which, being in resonance with the antenna circuit A L^3 E causes the latter to radiate electric waves of a definite length at a definite group frequency. The frequency of the individual electric waves is above the range of audibility as is customary in the case of energy radiated from an antenna. G^2 is an alternator having a frequency different from that of G^1 , and when the key K^2 is closed it supplies current to the step-up transformer T^2 , which, in turn, charges condenser C^2 .

$L^2 S^2 C^2$ is an oscillatory circuit which has a vibration period different from that of $L^1 S^1 C^1$ and which, being in resonance with the antenna circuit A L^4 E causes the latter to radiate electric waves of a definite length and at a definite group frequency, but of different length and different group frequency from the length and group frequency of the wave emanating from the set $G^1 T^1 L^1 S^1 C^1$. Thus when keys K^1 and K^2 are closed, antenna A radiates two series of electric waves of two different lengths or wave frequencies at two different group frequencies simultaneously. In order to operate the receiving circuit tuned to the receiver-interrupter frequency, it is necessary to have keys K^1 and K^2 closed.

In Fig. 2, B is an antenna, connected with the two tuned antenna circuits B $L^1 L^5 C^3 E^1$ and B $I^2 L^6 C^4 E^2$, through the interrupters I^1 and I^2 respectively. M is a motor which operates the interrupters I^1 and I^2 at a predetermined rate. As clearly

appears from Fig. 2, wherein the interrupters I^1 and I^2 are provided with the same number of teeth or projections and wherein the interrupter I^2 is shown as closing the circuit between the coil L^6 and the antenna B , whereas, the contact arranged to be engaged by the teeth of the interrupter I^1 is substantially equi-distant from adjacent teeth of the interrupter, the interrupters I^1 and I^2 are so arranged as to connect the coils L^5 and L^6 alternately or in rotational sequence with the antenna B . The two antenna circuits are tuned to the two oscillation frequencies, or wave lengths, of the transmitter, and are also in tune with the oscillatory circuits $L^7 C^5$ and $L^8 C^6$, respectively. Rectifier R^1 and coupling coil L^9 receive oscillatory currents from the circuit $L^7 C^5$ through the stopping condenser D^1 . Rectifier R^2 and coupling coil L^{10} receive oscillatory currents from the circuit $L^8 C^6$ through the stopping condenser D^2 . The oscillatory circuit $L^{11} C^7 L^{13}$ is coupled to L^9 and is tuned to one of the group frequencies of the transmitting station. The oscillatory circuit $L^{12} C^8 L^{14}$ is coupled to L^{10} and is tuned to the other group frequency of the transmitting station. R^3 is a rectifier and N an electro-magnet. Coil L^{15} is coupled to L^{13} , and L^{16} is coupled to L^{14} . Whenever I^1 closes the antenna circuit $B I^1 L^5 C^3 E^1$, unidirectional current impulses are induced in the untuned circuit $L^{15} R^3 L^{16} N$. These current impulses have a frequency corresponding to that of one of the group frequencies of the transmitting station, but come in sets which have a rate corresponding to that of interrupter I^1 . Whenever I^2 closes the antenna circuit $B I^2 L^6 C^4 E^2$, unidirectional current impulses are induced in the circuit $L^{15} R^3 L^{16} N$ of a frequency corresponding to that of the other group frequency of the transmitting station, and in sets having a rate corresponding to that of interrupter I^2 . The tuned reed Q is responsive to the combined rate of these two sets of current impulses, and when this combined rate is of the proper value, Q is set in vibration and makes and breaks the circuit $Q U V$, comprising the reed Q , the battery U and the telephone receiver V , and signals of a definite pitch, are heard in the telephone V . It should be noted that these signals cannot be received at V unless the corresponding wave length and wave group circuits at the transmitting and receiving stations are in tune with each other, and the vibrating reed Q is in tune with the combined rate of the interrupters I^1 and I^2 , thus making the system very highly selective. With regard to the interrupter rate, it should be noted that I^1 and I^2 make contact at different times, and so if each makes, say, 250 contacts per second, the circuit $L^{16} R^3 L^{16} N$ will re-

ceive 500 sets of current impulses per second, and the reed Q should be tuned to 500 vibrations per second, each set of current impulses acting on Q like a single long impulse.

Fig. 3 is similar to Fig. 2, except in the final elements for receiving signals. Here, instead of the electromagnet N , reed Q , battery U and telephone V , of Fig. 2, there is a tuned oscillatory circuit $L^{30} C^{15} W$, composed of the coil L^{30} , condenser C^{15} and telephone W , coupled to the coil L^{29} of the untuned circuit $L^{27} R^4 L^{28} L^{29}$.

When the combined rate of the sets of unidirectional current impulses in circuit $L^{27} R^4 L^{28} L^{29}$ corresponds with the period of the tuned oscillatory circuit $L^{30} C^{15} W$, currents are induced in the latter and signals are received in W .

In Fig. 4, G^3 and G^4 are alternating current generators of different frequencies, supplying current to transformers T^3 and T^4 , and controlled by keys K^3 and K^4 , respectively. Condensers C^{17} and C^{18} are charged by transformers T^3 and T^4 respectively, and discharge through the oscillatory circuits, $C^{17} L^{31} S^3$ and $C^{18} L^{32} S^4$ which have different periodicities. $C^{17} L^{31} S^3$ is inductively coupled, through the coil L^{33} , with the antenna circuit $A^1 I^5 L^{33} E^5$, and $C^{18} L^{32} S^4$ is inductively coupled, through the coil L^{34} , with the antenna circuit $A^1 I^6 L^{34} E^5$. A^1 is an antenna and E^5 a ground. I^5 and I^6 are interrupters, mechanically connected to, and operated by the motor M^2 . The contacts of these interrupters, as shown, are so arranged as to connect first one antenna circuit $A^1 I^5 L^{33} E^5$, and then the other antenna circuit, $A^1 I^6 L^{34} E^5$ to the antenna A^1 . When keys K^3 and K^4 are both closed, antenna A^1 , radiates two series of electric waves of two different definite lengths or wave frequencies at two different definite group frequencies, these wave groups being sent out in sets by the respective interrupters I^5 and I^6 at definite "set rates," these "set rates" corresponding to the rates at which the respective interrupters make contact.

In Fig. 5 is shown a modified form of receiving system adapted to be used in connection with a transmitting system such as is shown in Fig. 4. Such modified receiving system comprises an antenna B^2 forming a part of the two tuned antenna circuits $B^2 L^{38} C^{23} E^6$ and $B^2 L^{38} C^{24} E^6$. These two circuits are tuned to the two wave lengths of the transmitter by means of the inductance coils, L^{35} and L^{36} , and the variable condensers, C^{23} and C^{24} , respectively. Oscillatory circuit $L^{37} C^{19}$ is tuned for resonance with antenna circuit $B^2 L^{35} C^{23} E^6$, with which it is inductively coupled by means of L^{37} and L^{35} . Rectifier R^7 and coupling coil L^{38} receive oscillatory currents from circuit $L^{37} C^{19}$ through the stop-

ping condenser D^s . The oscillatory circuit $L^{41} C^{21} L^{43}$ is tuned to resonance with one of the group frequencies of the transmitting station, by means of the coils L^{41} and L^{43} and the variable condenser C^{21} . By means of the coupling coils L^{43} and L^{45} , circuit $L^{41} C^{21} L^{43}$ induces alternating currents in the untuned circuit $L^{45} R^9 L^{46} L^{47}$, which currents, being rectified by R^9 , act 10 as unidirectional impulses on the tuned circuit $L^{48} C^{16} W^1$.

The second antenna circuit $B^2 L^{38} C^{24} E^6$ is inductively coupled with the oscillatory circuit $L^{38} C^{20}$, with which it is in resonance. 15 Rectifier R^8 and coupling coil L^{40} receive oscillatory currents from $L^{38} C^{20}$ through the stopping condenser D^s . The oscillatory circuit $L^{42} C^{22} L^{44}$ is tuned to resonance with the second group frequency of the transmitting station, and, by means of the coupling coils L^{44} and L^{46} , it induces alternating currents in the untuned circuit $L^{45} R^9 L^{46} L^{47}$, which currents, being rectified by R^9 , act 20 as unidirectional impulses on the tuned circuit $L^{48} C^{16} W^1$.

Circuit $L^{48} C^{16} W^1$ comprises the coil L^{48} , the variable condenser C^{16} and the telephone receiver W^1 , and this circuit is tuned to resonance with the combined rate of the 30 interrupters at the transmitting station.

Each time the interrupter at the transmitting station which controls the transmitting antenna circuit corresponding to the receiver circuits $B^2 L^{35} C^{23} E^6$, $L^{37} C^{19}$ and $L^{41} C^{21} L^{43}$, closes its circuit, L^{47} , in the untuned circuit $L^{45} R^9 L^{46} L^{47}$, receives unidirectional current impulses at a definite rate corresponding to one of the group frequencies of the transmitting station, which impulses, in their action on circuit $L^{48} C^{16} W^1$ give the same effect as a single long impulse.

Each time the second interrupter at the transmitting station closes its circuit, L^{47} , in a similar manner to that just outlined, 45 receives unidirectional current impulses at a definite rate corresponding to the second group frequency of the transmitting station, and these impulses likewise give the same effect as a single long impulse in their action on circuit $L^{48} C^{16} W^1$.

When the keys K^s and K^e of the transmitting station shown in Fig. 4 are both closed, circuit $L^{48} C^{16} W^1$ of Fig. 5 will receive impulses successively at rates corresponding to the frequencies of interrupters I^s and I^e , of Fig. 4, respectively. These interrupter rates will be combined in their influence upon circuit $L^{48} C^{16} W^1$. Thus, if I^s and I^e each makes 250 contacts 60 per second, circuit $L^{48} C^{16} W^1$ will receive 500 impulses per second, and if it is tuned to this frequency of 500, it will respond, and oscillatory currents will be induced in it which will affect the telephone receiver W^1 .

It is evident, therefore, that in order to produce a signal in receiver W^1 , it is necessary to have electric waves of two definite lengths, each with its definite group frequency, and that these wave groups, moreover, must be sent out in sets, each at a definite "set rate." In other words, the receiver will respond only to a combination of two specific wave lengths, two specific wave-group frequencies, and two specific group-set rates. This, therefore, secures a remarkably high degree of selectivity.

In Fig. 6, G^s is a source of alternating current connected through a key K^s , with 80 a commutator H , which supplies current successively to the primary windings of transformer, T^s and T^e , respectively. The secondary windings of T^s and T^e form parts of the oscillatory circuits $C^{25} S^5 L^{49}$ and $C^{26} S^6 L^{50}$ respectively. These oscillatory circuits are inductively coupled to the antenna circuits $A^2 L^{51} E^7$ and $A^2 L^{52} E^7$ by means of the coils L^{51} and L^{52} , respectively.

The spark gaps S^5 and S^6 in the oscillatory circuits $C^{25} S^5 L^{49}$ and $C^{26} S^6 L^{50}$ respectively, are of different lengths, so that the spark frequencies (or group frequencies) of the groups of electric waves may have different values.

The alternator G^s should have a frequency of a higher order than that of the spark gaps, so that several alternations of current shall occur during each spark. Instead of the alternator, there may be a direct current generator or battery as a primary source of current for supplying the condensers C^{25} and C^{26} the spark gaps S^5 and S^6 and the oscillatory circuits $C^{25} S^5 L^{49}$ and $C^{26} S^6 L^{50}$ directly through the commutator H .

This arrangement permits the use of one generator instead of two. The commutator H also fills the place of the two interrupters and being operated at a definite rate, will supply sets of current waves successively to the two antenna circuits, each of these sets of current waves being composed of wave groups of a definite frequency, and each wave group being composed of waves of a definite length.

This invention is not limited to the particular apparatus herein described, nor is it limited to the transmission of signals, since the received energy can be utilized for the selective operation of various mechanical arrangements and devices, nor is the invention limited to any particular frequencies of waves, wave groups or group sets.

Having thus described my invention, I claim:

1. In a system of selective wave transmission, a transmitting station having means for emitting a plurality of co-existing series of waves in groups having different

- group frequencies, said wave group being emitted in sets having rates different from the wave frequencies and the wave-group frequencies.
- 5 2. In a system of selective electric wave transmission, a receiving apparatus having means which, by reason of appropriate tuning, are responsive to a combination of waves of two or more definite wave lengths
- 10 in wave groups of two or more definite frequencies, and means for facilitating reception of said groups in sets at a definite rate.
- 15 3. A method of selective electric wave transmission which consists in transmitting a plurality of wave groups, each having a predetermined group frequency, and each consisting of waves of predetermined wave length, these wave groups being emitted in sets having a predetermined set rate, and in
- 20 operating receiving apparatus by combinations of sets of wave groups.
4. A method of radio communication which consists in operating receiving apparatus by means of a combination of two
- 25 or more series of wave groups of different group frequencies, each series of groups consisting of waves of a definite wave length, the wave groups being received in sets at a definite rate.
- 30 5. A method of radio transmission which consists in transmitting a plurality of series of wave groups, each of such series having a predetermined group frequency and the different series consisting of waves of different predetermined wave lengths, these wave groups being emitted in sets having a predetermined set rate, and in operating receiving apparatus by the combined action of a plurality of series of wave groups.
- 35 6. A method of radio communication which consists in transmitting a plurality of electric waves in series of wave groups and group sets having frequency characteristics enabling said series to be separately received, and in operating receiving apparatus by means of the combined and simultaneous action of a plurality of series of sets of wave groups.
- 40 7. A method of wave transmission which consists in transmitting waves of different definite wave frequencies in groups of different definite group frequencies, transmitting said groups in a plurality of coexisting series of sets of definite set frequencies,
- 45 the sets of one of said series alternating with the sets of another of said series, and operating a receiving device as a result of the combined action of a plurality of said series of sets.
- 50 8. A method of wave transmission which comprises generating waves of predetermined wave frequencies in groups of different predetermined group frequencies, transmitting said groups in a plurality of coexisting series of sets of predetermined
- 55 set frequencies receiving said plurality of series at a receiving station by selecting the waves of the predetermined wave frequencies, selecting the groups of waves of the different predetermined group frequencies, 70 selecting the plurality of series of sets of groups, and causing a device to be operated as a result of the conjoint action of a plurality of series of the said selected sets.
- 9 9. A method of wave transmission which 75 comprises generating waves of different predetermined frequencies in groups of different predetermined group frequencies, transmitting said groups in a plurality of series of sets of predetermined set frequencies, receiving said plurality of series of sets at a receiving station by selecting different waves of the said predetermined frequencies, selecting the groups of waves of different predetermined group frequencies, combining the plurality of series of sets, and causing the operation of a device as a result of the conjoint action of a plurality of series of said sets.
- 10 10. A system of wave transmission comprising means for generating waves of predetermined frequencies, in groups of predetermined group frequencies, means for transmitting said groups in a plurality of coexisting series of sets of predetermined set frequencies, and receiving means comprising means tuned to selectively receive said waves, means tuned to respond to said predetermined group frequencies, means tuned to respond to a plurality of series of sets of the said predetermined set frequencies, and means arranged to be selectively operated as a result of the conjoint action of a plurality of 90 said selected series of sets.
- 11 11. A system of wave transmission comprising means for generating waves of different predetermined frequencies, in groups of predetermined group frequencies, means for transmitting said groups in a plurality of coexisting series of sets of predetermined set frequencies, and receiving means comprising means tuned to selectively receive said waves, means tuned to respond to the wave groups, means tuned to respond to a plurality of series of sets, and means arranged to be selectively operated as a result of the conjoint action of a plurality of said selected series of sets.
- 12 12. A system of wave transmission comprising means for generating waves of different predetermined frequencies, in groups of different predetermined group frequencies, means for transmitting said groups in a plurality of coexisting series of sets of predetermined frequencies and receiving means comprising means tuned to selectively respond to said wave frequencies respectively, means tuned to respond respectively to the wave groups, means tuned to respond to the plurality of series of sets, and means ar- 125
- 130

- ranged to respond selectively to the conjoint action of said selected plurality of series of sets. 13. A system of wave transmission comprising means for generating waves of different predetermined frequencies, in groups of different predetermined group frequencies, means for transmitting said groups in a plurality of coexisting series of sets of predetermined set frequencies, the sets of one of said series alternating with the sets of another of said series, and receiving means comprising means tuned to selectively respond to said wave frequencies respectively, means tuned to respond respectively to the wave groups, means tuned to respond to the plurality of series of sets, and means arranged to respond selectively to the conjoint action of said selected plurality of series of sets. 14. In a system of selective wave transmission, a transmitting station having means for emitting high frequency electrical etheric vibrations in groups, and a receiving station comprising circuits successively responsive to the frequency of the electrical etheric vibrations and the frequency of their group emission and a final responsive circuit tuned to a frequency differing from the foregoing but dependent upon their conjoint action in its functioning. 15. A receiving system for waves, comprising three cooperating elements electrically tuned respectively to three different frequencies, and a receiving device arranged to be operated as a result of the conjoint and successive action of said elements. 16. In a system of selective wave transmission, means for the transmission of high frequency waves in two series of groups, the group frequency of one of said series being different from the group frequency of the other of said series, and a single solid movable element arranged to be moved in response to the conjoint action of both of said series of groups. 17. In a system of selective wave transmission, means for the transmission of high frequency waves in a plurality of coexisting series of groups, the group frequency of one of said series being different from the group frequency of another of said series, and an electro-mechanical device arranged to be actuated in response to the conjoint action of said series of groups. 18. A receiving system for waves comprising a plurality of cooperating circuits tuned respectively to a plurality of wave group frequencies, and a device arranged to be actuated in response to the action of a plurality of said circuits. 19. A receiving system for waves, comprising a plurality of cooperating elements tuned respectively to a plurality of wave group frequencies, and a device arranged to be actuated in response to the conjoint action of a plurality of said elements. 20. A receiving system for waves, comprising a plurality of successively responsive circuits tuned respectively to a plurality of wave group frequencies, and a device arranged to be actuated in response to the conjoint action of a plurality of said circuits. 21. A receiving system for waves comprising a plurality of successively responsive elements electrically tuned respectively to a plurality of different wave group frequencies, and a device arranged to be actuated in response to the conjoint action of a plurality of said elements. 22. In a system of wave transmission, the combination with means for transmitting a plurality of series of groups of waves of different group periodicities, of a receiving station comprising a plurality of cooperating elements tuned to said periodicities respectively, and a device arranged to be actuated in response to the combined action of a plurality of said elements. 23. In a system of wave transmission, the combination with means for transmitting a plurality of co-existing series of groups of waves of different group periodicities, of a receiving station comprising a plurality of cooperating successively acting elements tuned to respond to said plurality of series of groups respectively, and a device arranged to be actuated in response to the combined action of a plurality of said elements. 24. In a system of selective wave transmission, the combination with means for generating a series of waves, of means for impressing upon said waves a series of periodic variations, and means for receiving said waves comprising two elements tuned to respond to said waves and said variations respectively, and a third element tuned to a frequency different from the wave frequency and the periodic variation frequency but dependent in its functioning upon the conjoint action of said first-mentioned two elements. 25. In a system of selective wave transmission, the combination with means for generating a series of waves, of means for impressing upon said waves a series of periodic variations, and means for receiving said waves comprising two elements tuned to respond to said waves and said variations respectively, and a third element tuned to a frequency different from the wave frequency and the periodic variation frequency but dependent in its functioning upon the conjoint and successive action of said first-mentioned two elements. 26. In a system of selective wave transmission, the combination with means for generating a series of waves, of means for

impressing upon said waves a series of periodic variations, and means for receiving said waves comprising two elements electrically tuned to respond to said waves and said variations respectively, and a third element electrically tuned to a frequency different from the wave frequency and the periodic variation frequency but dependent in its functioning upon the conjoint action of said first-mentioned two elements.

27. In a system of selective wave transmission, the combination with means for generating a series of waves, of means for impressing upon said waves a series of periodic variations, and means for receiving said waves comprising two elements electrically tuned to respond to said waves and said variations respectively, and a third element electrically tuned to a frequency different from the wave frequency and the periodic variation frequency but dependent in its functioning upon the conjoint and successive action of said first-mentioned two elements.

28. In a system of selective wave transmission, the combination with means for generating waves, of means for simultaneously impressing upon said waves a plurality of series of periodic variations having different frequencies respectively, and means for receiving said waves comprising elements tuned respectively to said frequencies, and a device arranged to be controlled as the result of the conjoint action of said elements.

29. In a system of selective wave transmission, the combination with means for generating waves, of means for simultaneously impressing upon said waves a plurality of series of periodic variations having different frequencies respectively, and means for receiving said waves comprising elements tuned respectively to said frequencies, and a device arranged to be controlled as the result of the conjoint and successive action of said elements.

30. A system of wave transmission comprising means for simultaneously generating a plurality of series of waves, means for simultaneously impressing upon each of said series of waves a series of periodic variations, said variations having different frequencies respectively, and means for receiving said waves including a plurality of elements tuned to respond to said frequencies respectively, and a device arranged to be controlled as a result of the conjoint action of said elements.

31. A system of wave transmission, comprising means for generating a plurality of series of waves, means for simultaneously impressing upon each of said series of waves a series of periodic variations, said variations having different frequencies respec-

tively, and means for receiving said waves including a plurality of elements tuned to respond to said frequencies respectively, and a device arranged to be controlled as a result of the conjoint and successive action of said elements.

32. A system of wave transmission, comprising means for generating a plurality of series of waves, of means for simultaneously impressing upon each of said series of waves a plurality of series of periodic variations, said variations having different frequencies respectively, and means for receiving said waves including elements tuned to respond to a plurality of said frequencies respectively.

33. A system of wave transmission comprising means for simultaneously generating a plurality of series of waves, of means for simultaneously impressing upon each of said series of waves a plurality of series of periodic variations, said variations having different frequencies respectively, means for receiving said waves including elements tuned to respond to a plurality of said frequencies respectively, and an element controlled by the conjoint action of said first-mentioned elements and tuned to respond to the combined action of two of said series of variations.

34. A method of wave transmission which consists in generating waves, impressing upon said waves a plurality of series of periodic variations, said variations having different frequencies respectively, selectively receiving said waves upon elements tuned to said frequencies respectively, and causing the operation of a receiving device as a result of the conjoint action of said elements.

35. A method of wave transmission which consists in generating waves, simultaneously impressing upon said waves a plurality of series of periodic variations, said variations having different frequencies respectively, selectively receiving said waves upon elements tuned to said frequencies respectively, and causing the operation of a receiving device as a result of the conjoint and successive action of said elements.

36. The method of wave transmission which consists in generating a plurality of series of waves having different frequencies respectively, simultaneously impressing upon said plurality of series of waves respectively a plurality of series of periodic variations, said variations having different frequencies respectively, receiving said plurality of series of waves upon elements tuned respectively to said wave frequencies and to said variation frequencies, and causing the operation of a receiving device as a result of the conjoint action of said elements.

37. The method of transmitting energy,

- which consists in generating a series of waves having a predetermined frequency, impressing in said series of waves a plurality of series of periodic modifications having different frequencies respectively, selectively receiving said waves and variations, and controlling a receiving device as a result of the conjoint and successive action of said waves and variations.
- 10 38. A system for receiving radiant energy comprising two receiving circuits tuned to respond to periodic radiant impulses of different frequencies respectively, both of said frequencies being substantially above audibility, and a third circuit arranged to be controlled as a result of the conjoint action of said first-mentioned circuits and tuned to respond to impulses having a frequency different from each of said first-mentioned 20 frequencies.
39. The combination with means for receiving the energy of a series of impulses modulated at a plurality of frequencies, of means arranged to be controlled by the received energy for producing a current of electrical impulses having a frequency corresponding to one of said first-mentioned frequencies and means arranged to be controlled by said current of electrical 25 impulses for producing a current of electrical impulses having a frequency less than that of said first-mentioned current and bearing a fixed, definite relation to another of said first-mentioned frequencies.
- 5 40. In a selective system for the transmission of electro-radiant energy, the combination with transmission means arranged to emit electro-radiant oscillations having a predetermined high frequency and a plurality of series of periodic variations of different predetermined frequencies, of receiving means arranged to selectively receive said oscillations and said variations and to function under the control of said oscillations and said plurality of series of variations.
41. A carrier wave transmission system comprising means for producing a series of radio frequency impulses having simultaneously existent therein a plurality of series of variations of higher and lower frequencies respectively, said series of variations of lower frequency being within the range of audibility, a receiving circuit tuned to the frequency of said impulses and a second circuit tuned to said higher variation frequency, a rectifier interposed between said circuits, a second rectifier controlled by said second circuit, and a circuit controlled by 55 said second rectifier and tuned to a frequency less than that of said second circuit and within the range of audibility.
42. A carrier wave transmission system comprising means for producing a series of radio frequency impulses having simultaneously existent therein a plurality of series of variations of higher and lower frequencies respectively, said series of variations of lower frequency being within the range of audibility, a receiving circuit tuned to the 70 frequency of said impulses and a second circuit tuned to said higher variation frequency, a rectifier interposed between said circuits, a second rectifier controlled by said second circuit, and an indicator circuit controlled by said second rectifier.
43. A system for transmitting and receiving radiant energy, comprising means for transmitting radiant energy in such a form as to include two series of periodic impulses 80 having two different predetermined frequencies respectively, two receiving elements tuned to respond to said frequencies respectively, and a third receiving element tuned to respond to a frequency different from either of said first-mentioned frequencies and arranged to be controlled as a result of the cooperative action of said first-mentioned elements.
44. A system of selective energy transmission having at the receiving station local circuits responsive to impulses of different periodicities, in combination with a common circuit coupled to each of said local circuits and comprising a rectifier, and an independent circuit coupled to said common circuit and comprising a current detector.
45. A system of distant control comprising an aerial receiving circuit, a primary closed oscillatory circuit tuned to a predetermined frequency and arranged to be controlled by said aerial circuit, a controlling device, a plurality of secondary closed circuits tuned to respond to different secondary frequencies and arranged to actuate said controlling device, and means controlled by said primary closed circuit for controlling said secondary closed circuits.
46. A carrier wave transmission system comprising means for receiving and detecting the energy of a modulated wave, means for selecting a component of said detected energy, and means for detecting said selected component.
